UNITED STATES PATENT OFFICE.

RALPH S. PEIRCE, OF HINSDALE, ILLINOIS.

ELECTRIC LAMP.

1,321,242.

Specification of Letters Patent. Patented Nov. 11, 1919.

Application filed February 8, 1915, Serial No. 6,711. Renewed April 12, 1919. Serial No. 289,732.

To all whom it may concern:

Be it known that I, RALPH S. PEIRCE, a citizen of the United States, residing at Hinsdale, in the county of DuPage and State 5 of Illinois, have invented a certain new and useful Improvement in Electric Lamps, of which the following is a full, clear, concise, and exact description, reference being had to the accompanying drawings, forming a 10 part of this specification.

My invention relates to electric lamps and supports therefor and has for its object the provision of a construction whereby such lamps may have their base portions inserted 15 within the sockets of candle sticks, standards, or other socket supports.

In carrying out my invention I equip the lamp base with a portion adapted for reception within a socket usually without requiring any modification in the structure of the 20 socket or support carrying the socket. This base portion is changeable in size or cross sectional dimension or width to adapt it to differing sizes of sockets, such as the varying 25 sized candle receiving cups or sockets in the upper ends of candle sticks. There is preferably an expansion device of which the aforesaid lamp base portion constitutes a part and which part is a complement co- 30 acting therewith for effecting the necessary expansion of the portion of the lamp base that enters the socket to insure the firm assembly of the lamp and socket.

I will explain my invention more fully 35 by reference to the accompanying drawing showing the preferred embodiment thereof and in which Figure 1 is a view in elevation illustrating one embodiment of the invention; Fig. 2 is a view of part of the structure 40 illustrated in Fig. 1 taken in a direction at right angles to that in which Fig. 1 is taken, part of the structure shown in this view being indicated in section; Fig. 3 is a sectional view on line 3 3 of Fig. 1; Fig. 4 45 is a sectional view on line 4 4 of Fig. 2 but on a larger scale; and Fig. 5 is a perspective view of component parts of the structure.

Like parts are indicated by similar characters of reference throughout the different 50 figures.

Any suitable form of socketed support 1 may be used in embodying the invention, the support shown being in the form of a standard such as is commonly employed as a 55 candle stick. The standard illustrated is

formed of metal having a cup portion 2 which constitutes the socket of the support. The lamp 3 illustrated is an incandescent electric lamp having a filament 4 adapted for inclusion in circuit with current conductors 5 by means of a well known switch having a knob 6. The base 7 constituting the mounting for the glass bulb of the lamp includes an extension 8 for reception within the socket 2, this extension being desirably 60

in the form of a tubular stem having a side opening 9 near its upper end for the passage of the circuit wires 5 between the interior and exterior of the stem whereby the lamp may be adapted to a socketed support which does not have a longitudinal bore 70 for the passage of wire. By making the stem 8 tubular throughout the structure may also be well adapted to those supports through which wires may be extended upwardly to pass clear through the bore of the stem. The opening 9 may be provided with a bushing of insulation 10 to guard the conductors 5 and this opening may be continued through a downsetting sleeve 11 em- 75

ployed for affording connection between the stem 8 and the base of the lamp and which is held in fixed relation to said stem by a set screw 12. The stem 8 is desirably threaded upon its exterior to have threaded connection with the sleeve 11 at its upper end and with a finishing skirt 13 at its intermediate portion, said skirt abutting against the shoulder 14 integrally formed with the stem 8. This skirt desirably has an outsetting 80 flange 15 which engages the marginal portion of the socket to improve the appearance of the place of union between the lamp and its socketed support. I desirably employ two inverted cup-shaped washers 16 and 17 85

having downsetting spring fingers integrally formed therewith and which are inwardly curled as indicated at 16¹, 17¹ and within the interiors of which cups washers 18 and 19 are disposed. The lower washer 19 has threaded engagement with the lower portion of the stem 8 while the upper washer 18 is free to move upon the stem without turning. Before the lamp structure is inserted within the socket the threaded washer or nut 19 is 90 turned until the lower cup 17 engages the upper washer 18 and is continued to be turned until both washers 18 and 19 expand the cups 16 and 17 to have the most bulging 95 portion thereof slightly larger than the bore 100

105

110

of the socket 2. The inwardly curled ends 16¹, 17¹ of the spring fingers of the washers, when thus expanded, are themselves within the circle of the socket so that the entry 5 of the cups within the socket may be effected, such entry being followed by the compression of the spring fingers of the cups to bring the cups into tight engagement with the socket. After the cups have thus been 10 brought into pressing engagement with the socket, such engagement may be improved as by turning the standard 1 in a clockwise direction, the cups turning with the standard, the lower cup forcing the threaded 15 washer 19 to turn upon the stem 8. To insure the movement of the washer 19 when the standard 1 is turned the washer is desirably provided with projections 20 which enter spaces between the spring fingers of 20 the cup 17. In expanding the cup 17 its movement along the stem 8 is forced, the upper end of this cup engaging the sliding washer 18 to cause it to expand the cup 16. Under certain conditions it might be impossible 25 to turn the socket 2 in which event it would suffice to secure the necessary relative motion by turning the lamp structure, a result which is readily feasible while the conductors 5 are detached from the supply circuit or if these conductors extend throughout 30 the length of the stem 8 and through the standard supporting the socket 2, a hollow passage for the conductors through the

standard being indicated at 21 by dotted lines.

35

While I have herein shown and particularly described the preferred embodiment of my invention I do not wish to be limited to the precise details of construction shown as changes may readily be made without departing from the spirit of my invention, but having thus described my invention I claim 40 as new and desire to secure by Letters Patent the following:—

40

An electric lamp structure including as 45 one of its elements an electric lamp having a threaded stem with a threaded washer thereon, in combination with a complementary element in the form of a socket into which said stem projects and which socket 50 contains a cup-shaped washer having fingers integrally formed therewith, said cup-shaped washer being engaged by said threaded washer which operates upon the fingers of the cup-shaped washer when the 55 stem and threaded washer are relatively turned to force these fingers into engagement with the socket to hold the lamp base and socket together.

55

In witness whereof, I hereunto subscribe 60 my name this fifteenth day of January A. D., 1915.

RALPH S. PEIRCE.
